HAND TRUCK

Arthur M. Barrett, Chicago, Ill., assignor to Barrett-Cravens Company, Chicago, Ill., a corporation of Illinois

Application November 17, 1949, Serial No. 127,816

9 Claims. (Cl. 214—65.4)

1

My invention relates to the class of material handling devices and, more specifically, is concerned with hand trucks for picking up, transporting and depositing containers, such as metal drums which have a beaded rim, or chime ring or equivalent means, at the end to be engaged.

Hand trucks provided with means for gripping the beaded rims or chime rings of containers for picking up and transporting the same are known, and I do not claim the same broadly.

My improvement is concerned with the type of truck in which the top of the drum is engaged and pulled toward the operator to initiate the raising of the drum. An example of this type of truck is disclosed in patent to Sabin, No. 1,513,863.

The general object of my invention is to simplify and reduce the cost of the truck as a whole, and a specific object is to simplify the construction and operation of the clamp or clutch device which makes connection between the truck and the rim of the container.

According to my invention, I provide a frame consisting of a central post or lever with a base of a width suitable to provide a two point support for the lower end of the barrel or drum, and to provide a mount for a pair of spaced supporting wheels.

Upon the central post or lever I mount, preferably by means of a pawl and ratchet adjustment, the clutch or clamping device. The clutch or clamping device has a self-engaging pivoted hook which has an inclined face for automatically raising the hook when it is presented to and pressed against the rim of the container to be lifted. The hook thus rides over the edge and adjusts itself to the height of the rim to be engaged or clamped. A lifting jaw is disposed below the point of the hook, so that in operation the hook will drop into position back of the rim to the full extent of its downward motion before the lower or lifting jaw engages under the bead of the rim to raise the load. Thus, a certain degree of lost motion is provided so that the rim of the container must first be engaged by the hook and the container tilted toward the operator before the lower jaw engages under the bead. Such initial tilting raises the center of gravity of the container and at the same time, inclines the container toward the operator sufficiently to gain the desired stable three point support upon the truck before the whole weight of the container is transferred to the truck by further swinging motion of the handle or lever toward the operator. The hook first engages the container, then angular motion of the lever or handle about the

2

axis of the wheels tilts the container on its adjacent lower edge and proceeds to take up the slack between the container rim and the lower jaw. By the time the lower jaw has engaged the rim, the container and the truck have been tilted into a position where the angularity of the handle or lever gives the weight of the operator a satisfactory leverage for applying the lifting force necessary to actually lift the container from the floor.

The novel organization of the clutch or clamping device may obviously be employed on any suitable frame and to any object to which it is applicable. However, the simplicity of the clutch or clamping device is, in the preferred form of my invention, matched by the simplicity of the truck frame to provide an efficient, simple device which can be constructed at low cost.

Now, in order to acquaint those skilled in the art with the manner of constructing and using devices in accordance with the principles of my present invention, I shall describe in connection with the accompanying drawings a preferred embodiment of my invention.

25 In the drawings:

Figure 1 is a perspective view of the hand truck of my present invention;

Figure 2 is a front elevational view of the clamp construction of my present invention with the front vertical plate member removed to show the mounting of the clamp jaws and the means between the standard and the clamp construction for vertically positioning the clamp construction;

Figure 3 is a partial plan view of the clamp construction shown in Figure 2, with the front vertical support plate in assembled position;

Figure 4 is a side elevational view of the hand truck of Figure 1, showing the manner in which the truck is supported in a substantially erect position; and

Figure 5 is a side elevational view of the hand truck of Figure 1, having a barrel in clamped position, showing the manner in which the truck is supported in a substantially horizontal position.

Referring now to Figure 1, there is shown a hand truck, indicated generally by the reference numeral 10, adapted for engaging, transporting and depositing various forms of containers as, for example, drums, barrels and the like. The hand truck 10 comprises a tubular standard 11, preferably of square cross-section, which is rigidly secured, as by welding, at its lower end to a transverse tubular frame member 12 of circular cross-section in the embodiment illus-

trated, centrally of the ends thereof. The transverse member 12 is supported by a pair of wheels 14 and 15 which are rotatably mounted thereon, in a conventional manner, at the opposite ends thereof. The upper end of the standard 11 is provided, in a suitable manner, with a handle 13 substantially of U-shaped configuration, the ends of which extend upwardly. The opposite ends of the handle bar 13 are adapted to be gripped by an operator for facilitating the maneuvering of the hand truck 10.

A rearwardly extending U-shaped tubular frame of circular cross-section, indicated generally at 16, is provided at the base of the truck for supporting the standard 11 in a horizontal position. The frame 16 is formed with a bight portion 17 and a pair of legs 18 and 19 which extend divergently from either end thereof. The forward ends of the legs 18 and 19 are bent downward at substantially a right angle and are secured, as by welding, to the transverse frame member 12 adjacent the ends thereof, inwardly of the wheels 14 and 15. A second transverse tubular frame member 20, of circular cross-section, spaced from the transverse frame member 12, is secured centrally of its ends to the standard 11 by means of a U-shaped bracket member 21. The ends of the transverse frame member 20 are one each secured, as by welding, to one each of the right angle bends in the intermediate portions of the legs 18 and 19 of the frame 16. In order to increase the rigidity of the frame 16, a tubular member 22 is secured, as by welding, at its one end to the central portion of the bight 17 of frame 16, and at its other end to the transverse frame member 12 centrally of the ends thereof at the junction of the standard 11 with the frame member 12. When the standard 11 is tilted rearwardly, the bight portion 17 of the frame 16 is adapted to engage the ground for supporting the standard 11, with or without a load, in a substantially horizontal position as is shown in Figure 5.

In order that the standard 11 may be supported in an erect position, a supporting frame structure, indicated generally at 23 is provided adjacent the lower forward portion of the standard 11. The structure 23 comprises a pair of sleeve members 24 and 25 journaled on the transverse frame member 20, one on each side of the standard 11. Secured, as by welding, at right angles to the sleeve members 24 and 25 are the ends of a pair of legs 26 and 27 respectively. Interconnecting the legs 26 and 27 and secured thereto in a suitable manner is a supporting plate member or saddle 28 in the shape of a cylindrical segment, in the particular embodiment illustrated, conformably formed to receive a barrel or like cylindrical container. It will be understood that the supporting plate member 28 may be of a shape other than that of a cylindrical segment so that containers other than those of cylindrical shape may be transported with the hand truck 10 of my present invention. When it is desired to position the truck in an erect position, the standard 11 is tilted forwardly a short distance, causing the lower ends of legs 26 and 27 to swing away from the transverse frame member 12 and to engage the ground, thus forming a substantially inverted Y-shaped frame, which is very stable. When the hand truck 10 is in any position other than erect, the lower ends of legs 26 and 27 rest against the transverse frame member 12 and together with the plate member 28 form a support for the lower portion

of a container when being transported by the truck 10.

A clamp construction, indicated generally by the reference numeral 30, is adjustably and slidably mounted for vertical positioning on the standard 11 and is provided for gripping a container at the upper rim portion adjacent one side thereof. The clamp construction 30 is best shown in Figures 2 and 3, and comprises a housing 10 including a pair of parallel spaced apart plate members 31 and 32, one disposed on each side of the standard 11. The plate members 31 and 32 are maintained in spaced relation by means of a plurality of spacer sleeve members 33, four in number in the embodiment shown, which are held in assembled relation by means of a plurality of rivets 34. A pair of the sleeve members 33 are placed one on each side of the standard 11, adjacent the upper portions of the plate members 31 and 32, and a pair of the members 33 are placed one on each side of the standard 11 adjacent the lower portions of the plate members 31 and 32, to keep the clamp construction 30 aligned with the standard 11 so as to allow it to be moved easily up and down the latter. A tubular roller 35 is journaled on one of the sleeve members 33 adjacent the lower portions of the plate members 31 and 32 for further guiding the clamp construction 30 and for an additional purpose to be described hereinafter.

Pawl and ratchet means are provided between the clamp construction 30 and the standard 11. Such means comprises a plurality of ratchet teeth 36 formed along one vertical side of the standard 11. A bell crank 37 is pivotally mounted at 38 in a known manner, between the plate members 31 and 32 and the bell crank 37 has teeth 39 formed on its one arm adjacent the end thereof, which teeth are adapted to engage with the ratchet teeth 36 on the standard 11 for maintaining the clamp construction 30 in one of a plurality of vertical positions. The teeth 39 of the bell crank 37 are biased into engagement with the teeth 36 of the standard 11 by means of a spring 40, one end of which engages the one arm of the bell crank 37 and the other end of which engages the sleeve member 33 adjacent the lower portion of the plate members 31 and 32. The spring 40 is suitably secured intermediate its ends, at 41, to the plate member 31. A handle 42, having an annular finger guard flange 43, is mounted on the other arm of the bell crank 37 so that the bell crank may be rocked about its pivot 38 when it is desired to disengage the teeth 39 from teeth 36 for permitting the clamp construction 30 to be lowered on the standard 11. It will be understood, that when raising the clamp construction 30 the bell crank 37 need not be manually manipulated as the teeth 39, by virtue of their shape, will slide over the teeth 36. When the upward movement is stopped, the teeth 39 are urged into engagement with the adjacent teeth 36 by the spring 40.

The clamp construction 30 further comprises a first jaw member 45 pivotally mounted between the plate members 31 and 32 about a fixed axis 46. The jaw member 45 has formed adjacent its outer end an angularly, downwardly and inwardly directed arm portion 47, which arm portion 47 has a leading edge adapted to serve as a camming surface for causing the member 45 to rotate clockwise, as viewed in Figure 2, when the leading edge is urged into contact with the upper edge of a fixed object. The outer end 75 of the arm portion 47 of jaw member 45 is

adapted to engage the inner surface of the upper rim portion of a container. An extension portion 51 is formed integrally with the jaw member 45 and is provided so that the operator may manually retract the arm portion 47 of the jaw member 45 from engagement with the inner surface of the upper rim portion of a container after the latter has been deposited in the desired location.

A second jaw member 48 is pivotally mounted between the plate members 31 and 32 about a bolt 44, spaced from axis 46, extending through the plate members 31 and 32, and held in assembled position by means of a nut 50. The jaw member 48 has a sharp edged end which is adapted to engage the lower edge of the outer rim portion of a container.

A spring 49 is mounted to the plate member 31 at 50. One end of spring 49 engages one end of the jaw member 45 and the other end engages the intermediate portion of jaw member 48 so as to cause rotation of the jaw members 45 and 48 in a counterclockwise direction as viewed in Figure 2. The aforescribed roller 35 acts as a stop for the one end of jaw member 48 to limit rotation thereof in a counterclockwise direction.

The following is a brief description of the manner of using the hand truck of my present invention:

The operator must first adjust the clamp construction 30 so that the arm 47 of the jaw member 45 is located approximately at the height of the container to be picked up, with the edge of jaw member 48 about one or two inches below the lower edge of the rim portion thereof. If the clamp construction 30 must be raised, the construction need only be urged upward the required amount. If the construction must be lowered, the handle 42 must be pulled upward so as to disengage the teeth 36 and 39 on the standard 11 and crank arm 37 respectively. After the construction has been lowered to the desired height, the handle 42 need only be released, which permits the spring 40 to urge the teeth 39 into engagement with the adjacent teeth 36, thereby holding the construction against vertical movement. The truck 10 is then moved adjacent to the container while being maintained substantially erectly until the leading edge of arm 47 of jaw member 45 contacts and slides over the upper edge of the container into engagement with the inner surface of the upper rim of the container. The operator must then put his foot on the bight portion 17 of the support frame 16 and while the frame 16 is thus held steady, he may pull the upper portion of the truck towards him until the member 48 engages the lower edge of the outer rim portion of the container. Upon further movement, the container is initially raised from the ground. After the hand truck has been tilted rearwardly an amount to raise the container from the ground, the truck may be pushed to the location where the container is to be deposited. At the desired location, the container is deposited by tilting the truck forwardly until the container contacts the ground, at which time the upper jaw member 45 may be retracted by urging upwardly the extension portion 51 thereof, thus releasing the container and permitting the truck to be removed.

While I have shown and described what I believe to be a preferred embodiment of my invention, various rearrangements and modifica-

tions may be made therein without departing from the spirit and scope of my invention.

I claim:

1. In a truck, means for engaging the upper rim portion of a container adjacent one side thereof, said means comprising, a housing, a first jaw member pivotally mounted in said housing and having an outer end portion adapted to engage the inner surface of the upper rim portion of said container, a second jaw member pivotally mounted in said housing and adapted to engage the lower edge of the outer rim portion of said container and said jaw members being cooperatively related in a manner that when said rim portion is disposed therebetween, rearward tilting of the upper portion of the truck causes said first jaw member to effect rearward tilting of the container, which tilting causes said second jaw member to engage the lower edge of the outer rim portion of the container for raising the latter from the ground.

2. In a hand truck having a frame, a clamp construction carried on said frame for engaging the upper rim portion of a container adjacent one side thereof, said clamp construction comprising, a housing, a first jaw member pivotally mounted in said housing about a first axis, a second jaw member pivotally mounted in said housing about a second axis spaced from said first axis, the outer end of said first jaw member being formed with an angularly downwardly and inwardly directed arm portion, the free end of said arm portion being adapted to engage the inner surface of the upper rim portion of said container, the free end of said second jaw member being adapted to engage the lower edge of the outer rim portion, and said jaw members being cooperatively related in a manner that when said rim portion is disposed therebetween, rearward tilting of the upper portion of the truck causes said first jaw member to effect rearward tilting of the container, which tilting causes said second jaw member to engage the lower edge of the outer rim portion of the container for raising the latter from the ground.

3. The device of claim 2 wherein the leading edge of said arm portion of said first jaw member is directed angularly inwardly, thus serving as a camming surface for causing the first jaw member to rotate upwardly when the truck is maneuvered toward the container and the leading edge of said arm portion contacts the upper edge of the container, thereby causing said arm portion to slide over the upper edge and down into engagement with the inner surface of the upper rim portion of said container.

4. The device of claim 2 wherein means are provided for moving said clamp construction along said frame and for securing the same in one of a plurality of positions.

5. The device of claim 2 wherein the frame has a plurality of ratchet teeth formed therealong, means carried by said housing adapted to engage with the ratchet teeth on said frame for maintaining said housing in a stationary position therealong.

6. In a hand truck, a standard, a first transverse member secured to said standard adjacent the lower portion thereof, wheels journaled on the ends of said first transverse member, a second transverse member secured to said standard in spaced relation from said first transverse member, a pair of sleeve members journaled on said second transverse member, one at each side of said standard, a pair of legs, one secured to each of

said sleeve members and projecting laterally therefrom, and the outer end of said legs being adapted to engage the ground for supporting said standard in a substantially erect position when said standard is tilted slightly forwardly.

7. In a hand truck, a standard, a ground engaging frame having a transverse member secured to said standard adjacent the lower portion thereof, said ground engaging frame projecting substantially laterally rearwardly from said standard for supporting said standard in a substantially horizontal position, a pair of sleeve members journaled on said transverse member one at each side of said standard, a pair of legs, one secured to each of said sleeve members and projecting laterally therefrom, and the outer ends of said legs being adapted to engage the ground for supporting said standard in a substantially erect position when said standard is tilted slightly forwardly.

8. In a hand truck, a standard, a clamp construction carried on said standard for engaging the upper rim portion of a container adjacent one side thereof, a ground engaging frame having a transverse member secured to said standard adjacent the lower portion thereof, said ground engaging frame projecting substantially rearwardly from said standard for supporting said standard in a substantially horizontal position, a pair of sleeve members journaled on said transverse member, one at each side of said standard, a pair of legs one secured to each of said sleeve members and projecting laterally therefrom, a supporting plate carried between said legs against which the lower portion of a container is adapted to rest when the truck is tilted to lift said container, and the outer ends of said support members being adapted to engage the ground for supporting said standard in a substantially erect position when said standard is tilted slightly forwardly.

9. In a truck having a standard, means carried

by and selectively movable along said standard for engaging the upper rim portion of a container adjacent one side thereof, said means comprising a housing, a first jaw member pivotally mounted in said housing and having an outer hooked end portion, a second jaw member pivotally mounted in said housing, said second jaw member having an outer end which is disposed adjacent the side of the container spaced from the lower edge of the outer upper rim portion thereof when the outer end of said first jaw member is initially disposed in engagement with the inner surface of the upper rim of the container, said first jaw member after having been disposed in engagement with the inner surface of the upper rim of the container causing rearward tilting of the latter upon rearward tilting of the standard, which rearward tilting of the container causes the lower edge of the outer upper rim portion of the container to be moved into engagement with the outer end of said second jaw member, and said second jaw member effecting raising of the container from the ground upon further rearward tilting of the standard.
